COMBINED BOTTLE AND BASE THEREFOR

George L. Goodhue, Lancaster, Pa., assignor to Armstrong Cork Company, Lancaster, Pa., a corporation of Pennsylvania

Filed Jan. 7, 1965, Ser. No. 83,319

Term of patent 14 years

(Cl. D58—8)

FIG. 1 is a front elevational view of a combined bottle and base therefor showing my new design;

FIG. 2 is a top plan view thereof;

FIG. 3 is a bottom plan view;

FIG. 4 is a sectional view taken on the line 4—4 of FIG. 1;

FIG. 5 is a sectional view taken on the line 5—5 of FIG. 2;

FIG. 6 is a front elevational view of the bottle portion only, the supporting base being omitted;

FIG. 7 is a top plan view thereof;

FIG. 8 is a bottom plan view;

FIG. 9 is a sectional view taken on the line 9—9 of FIG. 6; and

FIG. 10 is a sectional view taken on the line 10—10 of FIG. 7.

The dominant features of my design reside in the portions shown in full lines.

I claim:

The ornamental design for a combined bottle and base therefor, substantially as shown and described.
